UNITED STATES PATENT OFFICE.

MYRON E. MOORE, OF WOODFORD'S, MAINE.

FIRE-ESCAPE.

SPECIFICATION forming part of Letters Patent No. 280,653, dated July 3, 1883.

Application filed February 6, 1883. (No model.)

To all whom it may concern:

Be it known that I, MYRON E. MOORE, a citizen of the United States, residing at Woodford's, in the county of Cumberland and State 5 of Maine, have invented a new and useful Fire-Escape, of which the following is a specification, reference being had to the accompanying drawings.

This invention relates to fire-escapes, and 10 has for its object to provide a simple, convenient, and safe means of exit from hotels and other large buildings, as well as ordinary residences, in case of fire. To this end it consists in the improved construction of the same, 15 which will be hereinafter fully described, and particularly pointed out in the claims.

In the drawings hereto annexed, Figure 1 is 20 a perspective view, showing my improved fire-escape in position for use. Fig. 2 is a vertical sectional view of the same. Fig. 3 is a rear view, showing the device in position in the room where it is attached. Fig. 4 is a perspective view of the frame of the device 25 extended. Fig. 5 is a perspective view, showing the frame folded, with the flexible ladder also folded; and Fig. 6 is a side view, showing the device in position and the ladder in the act of being paid out.

The same letters refer to the same parts in 30 all the figures.

A in the drawings designates the frame of my improved fire-escape, which is adapted to be secured at any window in the building where the device is used and sustain in position 35 the flexible ladder which forms the means of exit. The construction of the said frame is as follows:

B B represent the side frame-pieces, which are connected by cross pieces or braces C C 40 at their upper ends and near their lower ends.

F F are arched braces pivoted to the upper brace, C, and centrally to said braces are pivoted the legs D of a bail, E, which may thus be folded upon the frame.

To the under side of each of the arms D is 45 pivoted a pair of arms, G H, connected by a pivoted brace, I, enabling the said arms to be folded, as shown in Fig. 5 of the drawings.

To the inner arms, G G, are secured the upper ends of the sides of a suitably-constructed 50 flexible ladder, J, and to the outer arms, H, are secured the upper ends of a pair of flexi-

ble guards, K K, the lower ends of which are secured to the ladder at L, thus forming hand-holds or guards to assist timid persons in descending.

The lower ends of the sides of the flexible ladder have hooks M, adapted to be hooked over one of a series of rungs, N, connecting the sides of a frame, O, provided at its inner 55 end with points or prongs P, adapted to enter sockets Q in the wall of the building where the device is used. By means of this device the flexible ladder is held out from the wall of the burning building during operation, thus 60 enabling the inmates to descend with safety. The frame O is provided with a rung, N, for each story or floor of the building where a fire-escape is used, the ladders from the lower 65 floors being hooked to the inner, and those from the upper floors to the outer, rungs, thus 70 causing the several ladders to be well separated, and enabling those residing on the several floors to descend in safety at the same time.

The side pieces, B B, of the frame are provided with outwardly-bent brackets R at their lower ends, provided with perforations S to receive a rod, T, by means of which the frame is secured in position for operation to screw- 75 eyes U in the floor of the room where the device is to be used, and in front of the window. Three screw-eyes are preferably used, and a rod of sufficient length to enable the frame to be slid to one side of the window when folded 80 and not in use, and be covered and concealed by means of a suitable casing or cabinet; or the device may be entirely detached and kept at any desired place in the room.

To enable the device to be readily manipulated and moved into position, I provide the sides of the frame with rollers or casters V.

The operation of my invention will be readily understood from the foregoing description, taken in connection with the drawings hereto 85 annexed. After folding the frame, as shown, the flexible ladder is folded between the curved braces F upon the sides or arms of the bail E. In this condition the device is kept in the rooms where it is intended to be used. In 90 case of fire it is only necessary for the occupant of the room to move the device to the window, attach it, (if it is not already arranged to slide into position upon the rod which serves

to secure it,) and pay the ladder out of the window. The weight of the ladder will assist in pulling it out, and when it is nearly or quite paid out its weight will serve to lift the bail E 5 of the frame and pull it out over the sill, upon which it rests during operation. The arms G H sustain the ladder and guards at some distance from the wall of the building, and the bail E forms a guard which enables the inmates to step out upon the ladder in safety. The frame O is placed in position by the firemen, or by persons below.

I claim as my invention and desire to secure by Letters Patent of the United States—

15 1. In a fire-escape, the herein-described folding frame, consisting of side pieces connected by rungs, a bail pivoted to the upper ends of said side pieces, and downward - depending folding arms pivoted to the sides of said bail 20 and connected in pairs by pivoted braces, as set forth.

2. In a fire-escape, the herein-described folding frame, comprising the side pieces, the pivoted bail having arched braces between which 25 the flexible ladder may be folded, and rollers or casters journaled to the sides of the said side pieces, whereby the device may be readily moved into position for operation, as set forth.

3. In a fire-escape, the combination of the 30 side pieces of the frame pivoted to a rod connected to the floor of a room, in front of the window, the bail pivoted to the upper ends of the said side pieces, the arms pivoted to the sides of said bail, the pivoted braces connecting the 35 said arms, the flexible ladder secured to the inner arms, and the flexible guards secured to the outer arms and to the ladder, as herein described, for the purpose set forth.

4. In a fire-escape, the combination of the 40 herein - described frame, the flexible ladder secured to the same, and having hooks at its lower end, and a frame having points adapted to enter sockets in the wall of the building, at the base of the same, and provided with a series of rungs to which the flexible ladders leading from the several floors of the building 45 may be connected, as set forth.

In testimony that I claim the foregoing as my own I have hereto affixed my signature in 50 presence of two witnesses.

MYRON E. MOORE.
